LUBRICANT PUMP WITH REMOVABLE
PUMP ELEMENTSWerner Max Josef Jüllig, Atvidaberg, Sweden,
assignor of one-half to Robert Vogelgesang,
Södertorns Villastad, Sweden

Application May 22, 1951, Serial No. 227,705

Claims priority, application Sweden July 6, 1950

12 Claims. (Cl. 103—38)

1

The present invention refers to lubricant pumps with removable pump elements, and particularly relates to grease lubricating apparatus. Such apparatus are generally constructed with a grease receptacle located at the top and with plunger pumps arranged therebeneath in a circle about a central axis. The grease by reason of its stiff consistency will have to be pressed with some pressure to the inlet apertures of the plunger pumps, and this generally takes place through wing-shaped means rotating in the grease receptacle.

A technical requirement is that the pump elements shall be exchangeable, since in the pumping of grease considerable pressures are frequently produced and the grease always contains abrasive mineral particles, so that the pumps will be worn down comparatively rapidly. A number of constructions with exchangeable pump elements have been proposed, said elements being then generally arranged in a circle approximately midway of the apparatus in the vertical direction thereof while being adapted to be taken out in a radial direction, the connecting screw bonds for the pipe conduits to the places of lubrication being rigidly connected with the pump elements. In an apparatus of this description it is necessary first to disassemble the connecting screw bonds of the pipe conduits to permit a pump element to be removed. Furthermore, the elements will have to be pulled out in a radial direction horizontally, it being then conceivable that the apparatus is located near a wall so as to make the attaching screws of the elements relatively inaccessible.

The above-named disadvantages are avoided in the lubricant pump according to the present invention, which is substantially distinguished by the feature that the pump elements, with the upper portion of the apparatus removed, are arranged to be disassembled vertically upwards while being secured to a common plane bottom plate, which is rigidly connected with the pump housing and provided with openings having parts of a driving member common to all pump elements and situated underneath the bottom plate extending therethrough. This brings the advantage that it will be possible to have the elements screwed fast to a horizontal surface from which they may be lifted up vertically to be exchanged.

A form of embodiment of the invention will be described hereinbelow by way of example with reference to the accompanying drawings, wherein Fig. 1 illustrates a vertical section through the apparatus. The left hand side of Fig. 2 is a view of the apparatus upon removal of the receptacle, and the right hand side of Fig. 2 shows the worm gearing housed in the base of the apparatus. Fig. 3 is a perspective view of the apparatus upon removal of the receptacle. Fig. 4 is a perspective

2

tive view of the central shaft with a helical gear arranged thereon. Fig. 5 is a perspective view of the operating plate with appertaining pressure rods. Fig. 6 is a perspective view of the disk 5 for parallel movement. Fig. 7 is a perspective view of the pressure plunger with a set screw. Fig. 8 is a perspective view of the pump element. Figs. 9, 9a, 9b show a pressure plunger. Figs. 10, 10a show a plunger with a set screw and ball arresting means. Figs. 11, 11a and 12 show the set screw to a larger scale. Figs 13-15 show the pump element to a larger scale.

It will appear from Fig. 1 that the apparatus is composed of three principal parts, that is to say the upper part situated above the line A—A and having the low pressure portion built into the same, the intermediate part located between the lines A—A and B—B and containing the high pressure portion, and the lower part situated underneath the line B—B and containing the worm gearing for the operation of the apparatus.

The upper part

This part consists of the bottom 10 of a receptacle, which is rigidly connected with the wall 11 of the receptacle, covered at the top by a lid 12. The upper part is attached by means of screws 13 onto the intermediate part, and is tightened by means of a rubber ring. The bottom 10 of the receptacle has a round aperture provided at the centre thereof, said opening being terminated at the bottom by a perforated supporting plate 8 having a fine strainer 7 lying thereabove. The supporting plate 8 is rigidly connected with the bottom 10 of the receptacle by means of screws 9. Mounted at the centre of the supporting plate 8 is a hub 5 carrying an oblique pin 4, on which a conical body 1 is rotatably mounted. This body engages the supporting plate 8 through the pins 2 and 3 in a simple gear engagement so as to perform a rolling movement, as soon as the hub 5 with the oblique pin 4 is brought into a rotary movement. A wing, not shown, is rigidly connected with the hub 5 and ensures that the grease is fed in beneath the body 1, which by its rolling movement presses the grease through the strainer 7 and large openings in the supporting plate 8 to the inlet openings of the pump elements.

The intermediate part

About midway of its vertical dimension the pump housing 14 has a plane bottom 14c having the pump elements 15 screwed fast onto the upper side thereof. These pump elements whose dimensions in width decrease in a radially inward direction each contain a cylindrical bore, a pressure plunger 18, a bottom stopper 19a, and an attaching screw 16. For each element there is provided in the housing 14 a channel bore 14d establishing communication between the cylinder

space of the pump element and the outlet screw plug 17. In the present instance this screw bond has a check valve (ball, spring and plug) built into the same, which parts, however, are not necessary in principle for the functioning of the apparatus, inasmuch as the inlet and the outlet of the cylinder are positively governed by the mode of operation of the plunger to be described in the following. The ball valve only has for its object to relieve the pump, in order to increase the life thereof.

Mounted between the central aperture of the pump housing and the central aperture of the base 26 is a central shaft 27 formed at the middle portion thereof into an eccentric having the operating disk 25 mounted thereon. A disk 28 for parallel movement (see also Fig. 6) ensures that the operating disk cannot turn about its own axis but is only permitted to perform a circular translatory movement. To attain this, it engages, on the one hand, with the pump housing 14 through two guide rollers 23, and also engages the operating disk 25 through two guide rollers 24 (see also Fig. 5). Each point of the operating disk thus performs a translatory circular movement with a radius of the magnitude of the eccentricity of the eccentric 27. The pressure rods 21 rigidly connected with the operating disk 25 also participate in this movement. The shape of the rods 21 will appear from Fig. 5. These rods are provided with slits in their top portions, said slits being engaged by the eccentric shaft portion 18b of the plungers (see Fig. 7). The planetating motion of the pressure rods imparts to the plungers a rotary movement to and fro as well as a reciprocating axial movement. The first movement serves to govern the opening and closing of the inlet and outlet bores of the cylinder, in a manner such that the groove 18c (Fig. 9) of the plunger is alternately brought into communication with the induction bore 15c and the outlet bore 15d of the pump element (Fig. 14). The bore 15e (Fig. 14) has no function to fulfill, but is produced in the making of the bore 15d. On the other hand, said bore 15e is not detrimental, since the groove 18c of the plunger is never brought into communication with the same. The outlet bore 15d communicates through the bore 15f with the bore 15b (see Figs. 1 and 14). The bore 15f is terminated outwardly through the screw 15g shown in Fig. 3. Pressed into a recess 15a on the lower side 15h of the element (Fig. 13) is a ring 15j from hard copper (Fig. 13), which projects somewhat beyond the lower side of the element and has for its object to tighten the outlet passage of the element against the plane 14c of the housing 14 (Fig. 1).

The pump elements are retained in the apparatus by means of a plug 18a (Figs. 1 and 8) engaging into a radially directed bore in the ring 14a (Fig. 1), which is rigidly connected with the hub 14b of the pump housing 14. The plug 18a is accurately fitted into the element, and the inner end thereof is somewhat upset, whereby an efficient tightening effect is obtained for the pressure liquid in the cylinder space. The bond between the element and the plug is only a friction bond, however, which would not be capable per se to take up the relatively high liquid pressures frequently present in the cylinder. On the other hand, this is not necessary, inasmuch as the plug has an axial support by the hub 14b of the housing 14. The operating pressure is thus conveyed from the pressure rod 21 over

the plunger 18, the enclosed liquid and the plug 18a directly onto the hub 14b, without exerting any greater axial force on the element 15 than the corresponding force for overcoming the friction between the element 15 and the plug 18a. By a ball-shaped configuration of the outer end of the plug (see 18a in Fig. 8) the element may be swung upwardly as shown in Fig. 3, when the attaching screw 16 is removed.

The pump element is also retained by means of the screw 16, which powerfully presses the packing ring 15j (Fig. 13) against the plane 14c of the housing (Fig. 1). The head of the screw 16 fits with a small clearance into the bore 15k of the element (Fig. 15), but has a large clearance in the bore 15m of the element (Fig. 15) as well as in the packing ring 15j. The bore 14e in the plane 14c of the housing 14 (Fig. 1) is so large at the top that an annular space is produced between the bore and the screw, said annular space communicating with the bore 14d leading to the outlet screw bond.

The attaching screw 16 thus fulfills two objects, first to retain the pump element and, second to tighten the channel connection between the element and the pump housing.

The pressure plunger and the set screw are shown in Figs. 7, 9, 10, 11 and 12. The plunger 18 is formed as a crank with the crank pin 18b. The plunger head contains a smooth bore having the set screw 20 mounted therein. The set screw has a single thread with a great pitch, which is formed as a helical groove, the bottom of which has milled into the same a number of spherical recesses 20a, 20b, 20c. The plunger head contains a spring-loaded ball 19, which is fitted into the largest recesses, which thus serve as holding catches. The helix has a single convolution, the pitch of which is equal to the length of stroke of the pressure plunger. By turning the set screw one revolution, the whole length of stroke may thus be transformed into an idle movement. The outermost ball recesses 20a and 20c (Fig. 12) are milled to such a depth that the ball 19 cannot rise to the cylindrical surface of the stem portion of the screw. Hereby these ball recesses form limiting means for the turning movement. The remaining recesses are more shallow, so that a certain torque is required to turn the set screw to and fro, without preventing, however, a turning movement of the screw when applying a greater force. The length of the set screw is so adapted that, should the set screw be screwed out as far as it goes (that is to say, until the ball 19 is received in the ball recess 20c), the head of the set screw is caused to touch the inner wall of the housing 14 (Fig. 1). This abutment, which is known per se, has for its object to prevent a pump from sucking a larger quantity of liquid than the adjusted one, which might take place without this abutment on account of jolting or by too large a superatmospheric pressure on the suction side originating from the low pressure contrivance.

A coaxial arrangement of the pump plunger and the set screw ensures that the set screw does not perform any oscillatory movements, for instance as in the older construction described in the aforementioned patent.

If all of the lubricant outlets 17 are not to be used, the pump elements 15 associated with the non-used outlets can be installed without their plungers such as indicated by pump element 15x in Fig. 2 and the outlet sealed by a plug 34.

Coupling between the upper part and the intermediate part

Such coupling is effected by a resilient strap 21a (Figs. 1 and 4), which is mounted in two apertures in the central shaft 21. The strap engages a groove on the lower side of the hub 5 (Fig. 1). The strap as well as the groove are situated somewhat eccentrically so as to ensure that coupling is possible only in a definite relative position between the low pressure and the high pressure mechanisms. This is necessary to warrant that the conical body 1 exerts its greatest pressure on the grease, when the pump plunger performs its suction stroke, so that a filling of the plunger space as complete as possible will be obtained.

The lower part

The latter consists of the base 26 containing a worm gearing 28, 29 adapted to transmit the rotary movement of the outer driving shaft 31 onto the central shaft 27. The base is equipped at the top with a sliding surface 28a, so that the operating disk 25 will be guided between this surface and the lower side 14f of the housing 14. The lubricant pump described above and illustrated in the drawings only constitutes an example of embodiment of the invention and may be varied in its construction and details, without the principle of the invention being departed from.

What I claim is:

1. In a pump adapted to pump lubricants and the like the combination comprising a pump housing having a plane transverse bottom plate, a plurality of pump elements arranged radially on said bottom plate about a common vertical axis, means releasably securing said pump elements in place on said plate such that upon the release of said securing means said pump elements may be released vertically upwards, each said pump element comprising a body portion including a cylinder arranged radially of said vertical axis having an inlet port communicant with a source of the lubricant and an outlet port communicant with a channel in said plate leading to the exterior of said pump housing and a plunger element slidably in said cylinder, and eccentric driving means for the plungers of all said pump elements, said driving means comprising driving elements in releasable driving relation respectively with the radially outward end of each plunger, said driving elements extending upwardly through said plate, and eccentrically movable means disposed below said plate and connected with said driving elements for driving the same simultaneously.

2. A pump as defined in claim 1 wherein the releasable securing means for each of said pump elements includes a plug individual to and closing the radially inward end of the cylinder of each pump element, the portion of said plug within said cylinder being cylindrical and of substantially the same diameter as that of the cylinder and the plug portion outside of said cylinder including a ball-shaped end seated in a socket provided in a hub portion of said plate.

3. A pump as defined in claim 1 wherein the body portion of each said pump element decreases in width in a radially inward direction with the top and bottom faces thereof located in parallel planes, and the pump elements are disposed in closely spaced side-by-side relation.

4. A pump as defined in claim 1 wherein the releasable securing means for each of said pump elements includes a single attaching screw ex-

tending through a bore in the body of said pump element into said plate.

5. A pump as defined in claim 4 wherein the bore in the body of each pump element for the attaching screw constitutes also a portion of the outlet port of each pump element, the diameter of the screw being smaller than that of said bore to permit passage of the lubricant in the annular space thereby provided between the screw and wall of the bore.

10 6. A pump as defined in claim 5 wherein the channel in said plate leading to the exterior of the pump housing from each pump element includes an inlet end concentric and communicant with the screw receiving bore in the pump element, and a packing ring sealing the joint therebetween and which is compressed by said screw.

15 7. A pump as defined in claim 1 wherein the plunger of each pump element is provided with a stroke regulating member adjustable longitudinally of the plunger and arranged coaxially therewith and which engages the associated driving element of the driving means.

20 8. A pump as defined in claim 7 wherein the stroke regulating member for each plunger is constituted by a screw having a disk-shaped head and a single thread in the form of a helical groove of semi-round cross section and a pitch equal to the maximum of the plunger stroke, said groove having spaced recesses therealong and a spring-loaded retaining ball mounted in a recess in the plunger and selectively engageable with one of the recesses in said groove.

25 9. A pump as defined in claim 8 wherein the recesses in the helical groove of each plunger stroke regulating screw are comprised of a recess at each end of the groove and a plurality of other recesses distributed in uniformly spaced relation over the length of the groove.

30 10. A pump as defined in claim 9 wherein the recesses at the ends of the helical groove of each plunger are of such depth that the retaining ball cannot rise upwardly upon continued rotary movement of the screw and thereby serve as limit means for the rotary movement of said screw.

35 11. A pump as defined in claim 1 wherein the driving means of said plungers is comprised of a disc mounted horizontally in said pump casing below said plate and means effecting an eccentric motion of said disc in a horizontal plane about the said vertical axis of the pump, the driving elements for the plungers of the pump elements being secured to and along the periphery of said disc for effecting a corresponding translatory motion of said driving elements.

40 12. A pump as defined in claim 1 wherein at least one of said radially arranged pump elements has the plunger removed therefrom and further including means sealing the lubricant outlet associated therewith.
